BOILER

Max Guszmann, 45 W. 81st St., New York, N.Y.
Filed July 10, 1959, Ser. No. 826,314
7 Claims. (Cl. 122—235)

The present invention relates to a boiler and more particularly it relates to boilers which can be easily dismantled into several relatively small elements.

The present application is a continuation in part of my co-pending application Serial Number 794,308, filed February 19, 1959, and entitled: "Steamboiler."

It is an object of the present invention to provide a boiler comprising mild steel tubes which are welded together to form a plurality of water tube units, which can be individually dismantled and easily assembled to form the boiler whereby the assembly can be carried out in situ, e.g. at the location of ultimate use of the boiler, the individual units being sufficiently small to be transported into the space for the boiler through conventional doors or the like.

It is the further object of the present invention to provide means contributing to a highly economical and efficient structure whose individual units and sections thereof can be easily removed and/or replaced.

It is another object of the present invention to provide means ensuring in a boiler of the aforesaid structure rapid water circulation in a simple and effective manner.

Other objects and advantages of the present invention will become apparent from a further reading of the description and of the appended claims.

With the above and other objects in view, the present invention includes in a boiler, in combination, a fire-box including a wall having an outlet for combustion gases; a stack of flat water tube units, one unit at one end of the stack being located adjacent the wall of the fire-box, each unit including inlet means, outlet means, a set of spaced water tubes communicating with the inlet and outlet means, and wall means, secured to the water tubes and extending in the spaces between the same to form passage means through said units, said wall means of said units of said stack together forming flue wall means in the spaces between said water tubes and removable closure means for closing gaps between the perimetric portions of adjacent units and between the perimetric portion of said one unit and the wall of the fire box so that a tortuous flue passage communicating with the outlet of the fire box is formed by said closure means and the flue wall means, while each unit can be individually removed and replaced after removal of said removable closure means.

The present invention also encompasses in the inventive combination, a fire box, including a wall having an outlet for combustion gases, a stack of water tube units, one unit at one end of the stack being located adjacent to the wall of the fire box, each unit including a header having inlet means arranged in a row, outlet means arranged in a row, a set of spaced water tubes connected at the ends thereof to the headers, respectively and communicating with the inlet and outlet means, and wall means secured to said water tubes and extending in the spaces between the same transverse to the water tubes to form passage means through the unit, said wall means of a plurality of adjacent units together forming a plurality of continuous flue wall means in the spaces between the water tubes, said flue wall means having overlapping spaced portions with staggered ends, removable closure means for closing gaps between the perimetric portions of adjacent units and between the perimetric portion of said one unit and the wall of the fire box so that a tortuous flue passage communicating with the outlet of fire box

2

is formed by the closure means and said flue wall means, a first connecting tube means having a row of outlet members, respectively, detachably attached to the inlet means, a second connecting tube means having a row of inlet members, respectively, detachably attached to the outlet means, and a third connecting tube means, connecting said first and second connecting tube means having fresh water inlet means so that the water tube units are rigidly connected by said first, second and third connecting tube means and communicating with the same to establish water circulation, and whereby each unit can be individually removed and replaced after removal of the removable closure means.

Thus, the elements of the boiler which are detachably connected to each other may broadly comprise a first connecting tube supplying water to a plurality of water tube units from which the water flows to a second connecting tube or steam dome. Each of the water tube units is separately detachably connected to the first and second connecting tubes, respectively, so that individual water tube units can be easily detached for cleaning, repair or other reason. A third connecting tube connects the second connecting tube or steam dome with the first connecting tube. The fresh water supply is introduced into the third connecting tube. Fresh water passes from the third connecting tube into the first connecting tube, is then distributed to the individual water tube units and passes from the water tube units into second connecting tube or steam dome. A vaporized portion of the water leaves the steam dome through a steam conduit, while another portion of the water recirculates from the water-containing area of the steam dome through the third connecting tube towards the first connecting tube. Combustion gases formed in the fire box are lead through a tortuous passage formed by the individual water tube units so that the water in the water tube units is heated by the passing combustion gases. It is preferred, according to the present invention that the steam dome is not exposed to the combustion gases.

The novel features which are considered characteristic for the invention are set forth in particular in the appended claims. The invention itself, however, both as to its construction and its mode of operation, together with additional objects and advantages thereof, will be best understood from the following description of specific embodiments when read in connection with the accompanying drawings, in which:

FIG. 1 is an elevational view partially in cross section of a boiler constructed pursuant to the present invention;

FIG. 2 is a sectional view taken along the line 2—2 of FIG. 1;

FIG. 3 is a sectional view taken along the line 3—3 of FIG. 1;

FIG. 4 is a schematic elevational side view of another embodiment of a boiler according to the present invention;

FIG. 5 is a schematic elevational front view of the boiler shown in FIG. 4;

FIG. 6 is a schematic sectional view taken along the line 6—6 in FIG. 4;

FIG. 7 is an elevational view, partially in cross-section, of a boiler, according to another embodiment of the present invention;

FIG. 8 is an elevational frontal view taken in the direction of arrow VIII, FIG. 7; and

FIG. 9 is a plane sectional view taken along line IX—IX in FIG. 7.

Referring now more specifically to the drawings, and particularly to the embodiment of the present invention as shown in FIGS. 1—3, water tube units 1, 2 and 3 are shown forming a stack of water tube units. Fire box 4 includes wall 41 having an outlet 42 for combus-

tion gases formed in fire box 4. Water tube unit 3 located at one end of the stack of water tube units is arranged adjacent to vertical, tubular wall 41. The aforesaid tube units 1, 2 and 3 include tube means 11, 21 and 31, flanged inlet means 12, 22, 32 and flanged outlet means 13, 23 and 33, respectively. Each of the water tube units 1—2—3 forms a wall having passage means 14, 24, and 34, respectively, for guiding combustion gases from the fire box 4.

The passage means of adjacent water tube units are staggered, so that tube unit 3 communicates with fire box outlet 42. Passage means 14 of water tube unit 1 communicate with flue 43 for removal of the combustion gases from fire box wall 41 guided past water tube units 1, 2 and 3.

Removable closure means are provided for closing gaps between perimetric portions of adjacent water tube units and for closing the gap between wall 41 and water tube unit 3. These removable closure means comprise T-irons 15, 25, 35 and 45 welded along the outermost water tube units and of wall 41, and columns of shaped bricks 16, 26 and 36 stacked between adjacent T-irons and connected by refractory mortar. The lower portion of pit 4a of fire box 4 is defined by a refractory wall 44.

It can readily be seen that the combustion gases formed in fire box 4 will follow the tortuous paths via the aforesaid passage means indicated by arrows 46, 36, 26 and 16 to flue 43 and that each of the water tube units can be individually removed and replaced after removal of bricks 16, 26 or 36 and opening of the flanges or like coupling means of the respective inlet and outlet means.

Water tube unit 2, as illustrated in FIG. 2 comprises a pair of parallel, horizontal headers, namely header 27 and header 28. The unit also includes a set of water tubes 29 having the ends thereof, respectively, connected to headers 27 and 28. Header 27 is connected to flanged inlet means 22 and header 28 to flange outlet means 23. Walls 229 are arranged between adjacent tubes 29 and one of the headers. In the case of water tube unit 2—as illustrated—walls or baffles 229 are arranged between adjacent tubes 29 and header 27 but spaced from header 28 so that between adjacent tubes 29 and headers 28 passage means 24 for the passage of combustion gases according to arrow 46 are formed.

Header 27 communicates through inlet means 22 with first connecting tube 50, and header 28 communicates through outlet means 23 with a steam dome or collector drum 60. First connecting tube means 50 includes coupling means consisting of flanged outlet means 51, 52, 53 and 54 connected to corresponding flanged inlet means such as indicated by numerals 12, 22 and 32. Similarly, flanged outlet means 13, 23, 33 and flanged outlet means of wall 42 which will be described further below, connect with flanged inlet means 61, 62, 63 and 64 of drum 60. Second connecting tube 70 connects first connecting tube 50 with second drum or dome 60 and is provided at a location below drum 60 with fresh water inlet means 71.

The above described structure comprising the stack of water tube units, the fire box wall, first and second connecting tubes, the individual elements of which are detachably connected with each other, forms a rigid communicating structure in which a liquid can circulate. Steam or like heated medium will be discharged through outlet means 65 and the medium which is thus removed from the system will be replaced through fresh water inlet means 71. Circulation is enhanced by the temperature drop in second connecting tube or pipe 70 which is due to the introduction of fresh water into the second connecting pipe 70 and also to the arrangement of a portion of the second connecting tube 70 outside of insulated shell 90. Shell 90 is only schematically illus-

trated in FIG. 1, 2 and 3 and includes a fire box door as well as a removable section facing water tube units 1, 2 and 3 which section can be easily removed when one of the water tube units is to be disconnected and replaced. Shell 90 is of conventional design and does not form an essential part of the present invention. It is, however, preferred according to the present invention to expose a portion of tube 70 to lower temperatures than the remainder of the water-containing structure in order to increase water circulation throughout the system.

The boiler is illustrated in FIGS. 1 and 3 as comprising three detachable water tube units, the present invention however being not limited to any specific number of tube units.

15 The wall means forming fire box 4 comprise in addition to wall 41, vertical walls 47, 48 and 49 as well as an upper horizontal wall and a frontal vertical wall extending downwardly from the upper horizontal wall to a header 441. Each of these walls has spaced header tubes 20 and wall-forming tubes connecting the space header tubes and wall members between the header tubes and the wall-forming tubes, the tubular wall members of wall 41 are of such shape as to form outlet 42 for combustion gases between adjacent wall-forming tubes. Inlet and outlet 25 means are connected to the header tubes and in turn communicate with the first connecting tube 50 and drum 60, respectively.

As illustrated, walls 47 and 48 are detachably connected by a coupling or flange arrangement 442. It is 30 also possible to omit blind flange arrangement 442 and to make walls 47 and 48 integral. When walls 47 and 48 form an integral structure, the entire wall means of the fire box constitutes one detachable element. By arranging blind flange connection 442, the wall means of the fire 35 box are divided into two correspondingly smaller individually detachable elements.

The fire box forming wall means and the stack of tubes 40 units for the liquid to be heated are supported by a foundation 7 formed of bricks or the like and covered with sheet iron cover 8. However, it is also possible to 45 rest the boiler structure on a brick or the like foundation without interposition of sheet iron cover 8. In the latter case, preferably, the foot portions of the boiler structure are placed on and slightly embedded in a refractory mortar.

To prevent upward escape of combustion gases between adjacent water tube units and between water tube unit 3 and fire box wall 41, iron bars 5 and 6 are welded along and bridging the upper headers of adjacent units. 50 Bar means 9 is placed upon fixed bar sections 5 and 6 to the gap between the same.

By way of example only and the present invention not being limited to the following data, the various elements 55 illustrated in FIGS. 1-3 for instance having the following dimensions:

Length of individual tubes 14: 1500 mm. diameter; 3"; diameter of heads 23 and 24: 6"; diameter of first connecting tube 25: 8" diameter of steam drum 26: 24"; diameter of third connecting tube 27: 6"; diameter of water feed line 28: 1½"; steam conduit 40: 3".

60 The boiler may operate for instance at a pressure of about 200 lbs. and in accordance with the above dimensions will have a total heating surface of about 20 m². The above data are given by way of example only, the 65 invention not being limited to any specific dimensions of the boiler members.

As illustrated, the drum 60 is located outside fire box 4, a single feeder (first connecting tube means 50) supplies water to all water tube units and the wall means of the fire box, and intensive water circulation is effected through second connecting tube means 70.

FIGS. 4-6 schematically illustrate another boiler arrangement according to the present invention in which the stack of water tube units comprises units 11, 12, 13 and 45, and is arranged adjacent water tube wall 7 of

fire box 4. However, in the embodiment illustrated in FIGS. 4-6, wall 7 forms the rear wall and not one of the side walls of fire box 4, and the headers such as headers 23, 24 and 8 are rectangular in cross-section.

FIGS. 7-9 illustrate, somewhat schematically, another embodiment of the present invention, according to which the flue passage is defined by flue wall means or partitions which extend from unit to unit in horizontal direction so as to force the flue gases to follow a tortuous path as indicated by flow arrows in FIG. 7. From FIG. 9 it will be seen that each of the individual tube units 701, 702, 703, 704 and 705 has secured to the tubes of each unit, respectively, wall section means 711, 712, 713, etc. and that adjacent individual wall means form flue wall means defining in part flue passage means, through which the flue gases pass from fire box 4 to flue 43, as indicated by the sequence of arrows in FIG. 7.

Removable closure or seating means 716 indicated in FIG. 9 correspond to removable closure means 16, 26 and 36 of FIG. 3. Two overlapping spaced portions of the flue wall means having staggered ends and extending parallel to each other in horizontal or transverse direction are shown in FIG. 7 as including the wall means indicated by reference numeral 711, 712 and 713 on the one hand and 714 and 715 on the other hand. The fire box wall having an outlet for the combustion gases is indicated by reference numeral 721. Walls 711-713 and 714-715 extend in transverse direction to upright water tubes 730 of individual water tube units 701-705.

In order to close the gaps between the aforesaid walls of adjacent units T-irons 740 which rest with their horizontal bar on the edge portions of adjacent walls are provided while the vertical leg of each T-iron extends downwardly through the gap between the adjacent walls. Different means may be employed for closing gaps 741 (FIG. 9). For instance, the edge portions of adjacent walls may be bent upwardly, and a channel iron U-shaped in cross-section may be placed over the upwardly bent end portions, so that the downwardly extending parallel legs of the U-iron embrace the upwardly bent edge portions of the adjacent walls. Under certain conditions, when a sufficient draft in the direction of flue 43 is desired, separate members for closing gaps 741 may be dispensed with, since such gaps will then be either non-existent or so small that the same can be neglected for all practical purposes.

As illustrated in FIG. 9, individual water tubes 730 of each of the water tube units 701-705 are preferably arranged in two parallel rows with the tubes disposed in staggered rows relative to the other. It has been found that particularly advantageous utilisation of the heat content of the flue gases is achieved by thus arranging water tubes of each water tube unit in two staggered rows.

Individual wall portions or partitions 711-715 may also consist of perforated metal sheets or plates having perforations corresponding to the outer diameter of the tubes which are to extend through the individual wall portions. The perforated plates may be held in position on the tubes by various means known per se, for instance, by being welded to the adjacent outer tube surface on one or a few locations along the circumference of the respective tubes, or by fixing a flange at the desired part of the tube and allowing the perforated plate to rest thereon. It is of course also possible to produce perforated plates of refractory material which may rest on flanges or other supports attached to all or some of the water tubes of the resp. unit. Thus, it is possible that there might exist a slight gap between the perforated plates forming the wall means and the individual water tubes extending through the openings or perforations of the perforated plate. This, however, generally does not impair the efficiency of the boiler and, in some cases, even might be beneficial to the operation of the same.

The arrangement of the tubular elements in staggered relation leads to considerable advantages in the transfer

of heat onto the water or like medium conducting tubular elements, as so-called shadows of the stream of heating gases are reduced to a minimum.

In other words, as the stream of heating gases hits the tubular elements of one row the further transfer of heat on the second row of tubular elements is increased due to the staggered relation of the rows of tubular elements provided in each hollow section unit.

It is of particular interest to note the following: The known types of multi-tube water boilers with a high efficiency can only be erected in a limited space. In spite of reduced space and high efficiency, however, these boilers were not accepted by the market.

Heavy in weight and shipped in one piece, transport to the required boiler-room space remains difficult and repair of leakage is practically impossible. Price of such boilers is higher than that of the other types, even if the latter are operating less efficiently. Without ignoring the qualities as indicated above, the shortcomings of these types have been fully eliminated in the construction according to the invention.

This new construction has the following characteristics:

(a) This new multi-tube boiler can be transported in sections, which can be easily assembled and easily dismantled. This fact eliminates all difficulties of transport into the boiler-room, without any damage to concrete walls, pavement or any other parts of the surrounding area; assembly of the boiler can be performed just as easily by flanges and bolts.

(b) A steam-drum is disposed outside the furnace and a circulation-duct at the exterior; all this results in an intense water circulation, by which the specific output of the boiler is increased.

(c) Since the boiler is built, with the exception of the steam-drum, of tubes, its weight is considerably less than that of other types, which results in great economical advantage.

(d) No heavy equipment is needed for the production of these boilers. Elimination of expensive machinery affects the cost of the boiler favorably.

(e) By the simple addition of new sections, the boiler can be easily enlarged. This enables owner of such boilers to keep and enlarge the same with little cost involved, if need should arise, and avoid the purchase of a new boiler.

(f) This new boiler is flexible enough to be used in large or small factories, as well as in apartment houses; consequently, the economy obtained by the higher efficiency of this boiler will be quite apparent.

What is claimed as new and to be secured by Letters Patent is.

1. A multi-tube boiler comprising a flue, a fire box including vertical tubular wall means, one of said vertical wall means terminating in upper and lower header means, a plurality of spaced apart, sectional tube units stacked next to each other adjacent said one vertical wall means and substantially coextensive in height with the latter, further upper and lower header means, respectively, bounding said tube units and in communication therewith, means sealing said tube units and said one vertical wall means against the escape of combustion gases coming from said fire box, respective baffle means mounted on said one vertical wall means and on said tube units and extending in a direction transverse to said units, so that a tortuous path is provided for the combustion gases to pass said one vertical wall means and thereafter the remaining tube units, successively, while said gases are guided by said baffle means to said flue for discharge, drum means, first outlet means connected to said drum means, first connecting tube means in communication with all lower header means, second connecting tube means forming circulation means for a liquid when introduced in the latter and interconnecting said first connecting tube means with said drum means, inlet means for a liquid connected to said second connecting tube means, respective second

outlet means connecting all upper header means with said drum means, and respective coupling means located between and detachably joining all upper header means with said second outlet means of said drum means and said first connecting tube means with all lower header means, whereby said liquid is heated and circulates through said tube units, said drum means, said second connecting tube means and said first connecting tube means back to the lower header means for the purpose of transmitting a predetermined quantity of heat to said drum and thence through said first outlet means.

2. A multi-tube boiler according to claim 1, a plurality of tubes arranged in staggered relation to each other in each tube unit and in said one vertical wall means defining said fire box.

3. A boiler according to claim 1, said baffle means extending across and at predetermined heights and spaced from and in staggered relation to each other, so that the combustion gases flow in a first direction from said fire box transversely of an upper portion of said tube units and then in a second direction opposed to the first direction and across a lower portion of said tube units, whence said combustion gases are discharged through said flue.

4. A multi-tube boiler comprising a flue, a fire box including vertical tubular wall means, one of said vertical wall means terminating in upper and lower header means, a plurality of spaced apart, tube units, each tube unit forming a section located adjacent said one vertical wall means and being substantially coextensive in height with the latter, further upper and lower header means bounding each tube unit and in communication therewith, each tube unit and at least said one vertical wall means including at least two rows of tubes disposed in staggered relation to each other, the row of tubes in one unit being staggered to an adjacent row of tubes in the neighboring tube unit, drum means, first outlet means connected to said drum means, first connecting tube means in communication with all lower header means, second connecting the tube means forming circulation means for a liquid and interconnecting said first connecting tube means with said drum means, inlet means for a liquid located intermediate said drum and said first connecting tube means and connected to said second connecting tube means, respective second outlet means connecting all upper header means with said drum means, and respective coupling means located between and detachably joining all upper header means with said second outlet means adjacent said drum means and said first connecting tube means with all lower header means, whereby each of said tube units may be removed as a section while liquid when introduced through said inlet means is heated and circulates through the tube units, said drum means, said second connecting tube means and said first connecting tube means back to the lower header means for the purpose of transmitting a predetermined quantity of heat collected in said drum through said first outlet means.

5. A multi-tube boiler comprising a flue, a fire box having vertical tubular wall means, one of said vertical wall means terminating in upper and lower header means, a plurality of spaced apart, sectional tube units located adjacent said one vertical wall means and substantially coextensive in height with the latter, further upper and lower header means, respectively, bounding said tube units and in communication therewith, means releasably bridging said further upper header means at the top thereof, means sealing said tube units and said one vertical wall means in lateral direction thereof, respective baffle means mounted on said one vertical wall means and on said tube units, so that a tortuous path is provided for

the combustion gases coming from the fire box and passing along and upwardly of said one vertical wall means, thence downwardly of and thereafter upwardly of the remaining tube units, successively, while said gases are guided to said flue for discharge, drum means, first outlet means connected to said drum means, first connecting tube means in communication with all lower header means, second connecting tube means forming circulation means for a liquid and interconnecting said first connecting tube means with said drum means, inlet means for a liquid connected to said second connecting tube means, respective second outlet means connecting all upper header means with said drum means, and respective coupling means located between and detachably joining all upper header means with said second outlet means of said drum means and said first connecting tube means with all lower header means, whereby said liquid is heated and circulates through said tube units, said drum means, said second connecting tube means and said first connecting tube means back to the lower header means for the purpose of transmitting a predetermined quantity of heat from said drum through said first outlet means.

6. A multi-tube boiler according to claim 5, wherein said vertical tubular wall means forming said fire box are provided with further coupling means for detachably connecting said vertical tubular wall means with each other.

7. A multi-tube boiler comprising a flue, a fire box having vertical tubular wall means, one of said vertical wall means terminating in upper and lower header means, a plurality of spaced apart, sectional tube units located adjacent said one vertical wall means and substantially coextensive in height with the latter, further upper and lower header means, respectively, bounding said tube units and in communication therewith, respective baffle means mounted on said one vertical wall means and on said tube units, so that a tortuous path is provided for the combustion gases coming from the fire box and passing along and upwardly of said one vertical wall means, thence downwardly of and thereafter upwardly of the remaining tube units, successively, while said gases are guided to said flue for discharge, drum means, first outlet means connected to said drum means, first connecting tube means in communication with all lower header means, second connecting tube means forming circulation means for a liquid and interconnecting said first connecting tube means with said drum means, inlet means for a liquid connected to said second connecting tube means, respective second outlet means connecting all upper header means with said drum means, and respective coupling means located between and detachably joining all upper header means with said second outlet means of said drum means and said first connecting tube means with all lower header means, whereby said liquid is heated and circulates through said tube units, said drum means, said second connecting tube means and said first connecting tube means back to the lower header means for the purpose of transmitting a predetermined quantity of heat from said drum through said first outlet means.
